Primary Examiner — Karen S Acker*Assistant Examiner* — Wendy Arminio(74) *Attorney, Agent, or Firm* — George G. Wang; Bei & Ocean(57) **CLAIM**

The ornamental design for a lace fabric, as shown and described.

DESCRIPTION

FIG. 1 is a front view of a lace fabric in accordance with the present invention.

FIG. 2 is a reference view of FIG. 1 with broken lines shown therein to indicate the are of detail view, FIG. 5.

FIG. 3 is a back side view of FIG. 1.

FIG. 4 is a front perspective view of FIG. 1; and,

FIG. 5 is an enlarged detail view of area 5 circumscribed by broken line in FIG. 2.

For clarity, the lace fabric is shown on a black background environment that forms no part of the claimed design. The broke lines in FIG. 5 depict the boundaries of the enlarged detail view of the claimed design and form no part thereof.

1 Claim, 5 Drawing Sheets(56)
